UNITED STATES PATENT OFFICE.

PETER REINHALTER, OF PHILADELPHIA, PENNSYLVANIA, ASSIGNOR
TO QUINCY ELECTRIC DRILL COMPANY, A CORPORATION OF NEW
JERSEY.

ROCK-DRILL.

SPECIFICATION forming part of Letters Patent No. 734,364, dated July 21, 1903.

Application filed July 10, 1902. Serial No. 115,011. (No model.)

To all whom it may concern:

Be it known that I, PETER REINHALTER, a citizen of the United States, residing in the city and county of Philadelphia, State of Pennsylvania, have invented a new and useful Improvement in Rock-Drills, of which the following is a specification.

My invention consists of a new construction of a rock-drill which is especially adapted to be operated by means of power taken from an electric motor or other source of energy, whereby the great expense heretofore incurred in the installation of rock-drills, plants wherein steam-engines, hydraulic, pneumatic, or similar apparatus are employed is obviated, as is also the expense ordinarily incurred in connecting the drills with their motors and in providing for the frequent changes of position thereof and their distance from the prime motors because of the costly and cumbersome appliances usually necessary to transmit the power from the motors to the operative parts of the drills. By my invention such difficulties are dispensed with and I am enabled to place the source of power at any required distance (it may be thousands of feet) from the rock-drill, and the power being transmitted by means of flexible and extensible conductors all the movements of the drill are conveniently and economically accommodated.

To the above ends my invention consists in the novel arrangement of springs adapted to coact with the reciprocating drill-rod, provision being made for rendering said springs readily accessible and for permitting said drill-rod to be readily rotated with a minimum degree of friction.

It also consists in the novel construction of a cross-head having oppositely-located shoulders thereon, said shoulders being provided with ball-bearing devices, against which the extremities of the springs or cushioning devices employed are adapted to abut.

It further consists of novel details of construction, all as will be hereinafter fully set forth, and particularly pointed out in the claims.

Figure 1 represents a longitudinal sectional view of a rock-drill embodying my in-

vention, certain of the parts being shown in elevation. Fig. 2 represents a longitudinal sectional view of Fig. 1, certain of the parts being shown in elevation. Fig. 3 represents a section on line *x* *x*, Fig. 1, certain of the parts being shown in elevation.

Similar numerals of reference indicate corresponding parts in the figures.

Referring to the drawings, 1 designates a rock-drill, the same consisting of a cylinder 2, having the nose-piece 3, through which the lower extremity 4 of the drill-rod 5 passes, the same having a socket 6 therein for the reception of the shank of the tool.

7 designates a flexible shaft of any suitable construction, which is caused to rotate, preferably, by an electric or other suitable motor, said shaft being rotatably mounted in the bearings 8 and carrying the beveled gear 9, which is adapted to mesh with the beveled gear 10, which is mounted on the crank-shaft 11, which rotates in suitable bearings and is provided with the cranks 12, from which extend the connecting rods or links 13, in which are mounted the pins 14, which are in threaded or other engagement with the cross-head 15, the latter having the oppositely-located extensions 16 and 17, which are adapted to slide within the cylinder 2, the latter being provided with oppositely-located slots 18 to permit the entrance and movement of the pins 14. The shoulder 19 within the head 15 has in contact therewith a ring 20, the surface of which is provided with suitable bearings for the balls 21, which are held in position by the ring 22, with which contacts one extremity of the spring 23, the other end of the latter contacting with the head 24, which is in engagement with the extremity of the drill-rod 5 and is held in position with respect thereto by the pin or plug 25.

26 designates a closure for the upper portion of the head or cap 24, with which engages the member 27 of the device by which the desired rotation of the drill-rod 5 is effected; but as I make no claim to this feature *per se* I have deemed it unnecessary to describe the same in detail.

28 designates the member or ring of the other or opposite ball-bearing device, which

contacts with the contiguous shoulder of the cross-head 15, said ring being grooved for the reception of the balls 29, which are held in position by the contiguous ring 30, against 5 which contacts an extremity of the spring 31, the opposite end thereof abutting against the abutment or shoulder 32 of the drill-rod 5, which latter, it will be noted, passes freely through the head 15, while the upper and 10 lower extensions 16 and 17 thereof are freely guided in the cylinder 2, which is supported within the casing 33, which has attached thereto the extension 34, within which are contained the cranks, pins, connecting-links, 15 and their adjuncts.

The operation is as follows: The rotation of the flexible or other shaft 7 is imparted, through the medium of the beveled gears 9 and 10, to the crank-shaft 11 and thence by 20 the connections 13 and 14 to the cross-head 15, wherefrom it will be apparent that the reciprocation of the cross-head 15 through the medium of the springs 23 and 31, whose opposite extremities contact, respectively, with 25 the ball-bearing devices carried within the cross-head and with the abutments formed by the parts 32 and 24, will cause a positive and effective reciprocation to be imparted to the drill-rod 5, while the impact of the blows 30 therefrom can be readily transmitted to the desired point through the medium of the desired tool employed.

It will of course be understood that the drill-rod 5 may be rotated in any suitable or 35 desired manner, as will be familiar to those skilled in this art.

I desire to call especial attention to the feature of mounting the juxtaposed extremities of the springs 23 and 31, respectively, upon 40 the ball-bearing devices carried within the cross-head, since it will be seen that by this construction the rod 5 will be permitted to be rotated to the desired extent without undue friction and that by my novel construction 45 the principal operative parts can be readily assembled or disconnected at all times for the purpose of inspection or repairs. It will also be noted that by the employment of the oppositely-located springs 31 and 23 50 and by reason of the fact that the reciprocating movements of the drill-rod 5 are imparted thereto in each direction by said springs said drill-rod is cushioned during its movements in both directions, whereby the most effective 55 results are attained and the life of the apparatus is prolonged, as is evident.

While I have described my invention as being particularly applicable to be used in connection with an electric motor, it will of 60 course be understood that I do not limit myself thereto, as other equivalent forms of motors may be employed without departing from the spirit of my invention.

It will be apparent that various changes 65 may be made by those skilled in the art which will come within the scope of my invention, and I do not, therefore, desire to be limited

in every instance to the exact construction I have herein shown and described.

Having thus described my invention, what 70 I claim as new, and desire to secure by Letters Patent, is—

1. In a rock-drill, a cylinder, a cross-head 75 therein and having oppositely-located extensions, a drill-rod passing loosely through said cross-head, means carried by said cross-head and projecting through slots in the casing for reciprocating the cross-head, abutments upon opposite portions of said drill-rod, ball-bearing devices carried upon opposite portions of 80 said cross-head and received within said extensions, springs interposed between said abutments and ball-bearing devices, and means for reciprocating said cross-head.

2. In a rock-drill, a cylinder, a cross-head 85 therein, extensions on either side of said cross-head, ball-bearing devices located within said extensions, abutments upon opposite portions of the drill-rod, a drill-rod passing loosely through said cross-head, springs interposed between 90 said abutments and ball-bearing devices, and means for reciprocating said cross-head.

3. In a rock-drill, a cylinder, a cross-head 95 therein, a drill-rod passing through said cross-head, abutments on opposite portions of said drill-rod, ball-bearing devices in contact with said cross-head, springs interposed between said abutments and ball-bearing devices, openings in said cylinder, pins engaging said 100 cross-head and projecting from said openings, a crank-shaft, and connections from said crank-shaft to said pins.

4. In a rock-drill, a cylinder, a cross-head 105 therein, a drill-rod passing through said cross-head, abutments on opposite portions of said drill-rod, ball-bearing devices carried by said cross-head, springs interposed between said abutments and ball-bearing devices, openings in said cylinder, pins in engagement with 110 said cross-head and projecting through said openings, a crank-shaft having a plurality of cranks thereon mounted on opposite sides of said cylinder, and links common to said crank-shaft and pins.

5. In a rock-drill, a flexible shaft, suitable bearings therefor, a crank-shaft, gearing common to said flexible shaft and crank-shaft, a cylinder adjacent to which said crank-shaft is mounted, the cranks of the latter being located oppositely with respect to said cylinder, a cross-head in the latter having oppositely-located extensions, ball-bearing devices located within said extensions, pins extending from said cross-head, links connecting said 125 pins and cranks, a drill-rod passing through said cross-head, abutments on opposite portions of said drill-rod, and springs interposed between said abutments and the ball-bearing devices of the cross-head.

6. In a rock-drill, a flexible shaft, suitable bearings therefor, a crank-shaft, gearing common to said flexible shaft, a crank-shaft, a cylinder adjacent to which said crank-shaft

- is mounted, the cranks of the latter being located oppositely with respect to said cylinder, a cross-head in the latter, said cylinder having oppositely-disposed slots and a cross-head 5 having oppositely-located extensions covering the same, pins extending from said cross-head and working in said slots, links connecting said pins and cranks, a drill-rod passing through said cross-head, abutments 10 on opposite portions of said drill-rod, and springs interposed between said abutments and cross-head, in combination with ball-bearing devices carried by said cross-head and adapted to contact with the juxtaposed 15 ends of said springs, whereby said drill-rod can be rotated according to requirements with a minimum amount of friction.
7. In a rock-drill, a cylinder having oppositely-located slots, a cross-head movable 20 within said cylinder, a drill-rod mounted to reciprocate loosely through said cross-head, ball-bearing devices upon opposite sides of said cross-head, abutments upon opposite
- portions of the drill-rod, springs interposed between said ball-bearing devices and said 25 abutments upon opposite portions of the drill-rod and means connected with the cross-head and projecting through said slots for reciprocating the cross-head.
8. In a rock-drill, a cylinder having oppositely-located slots, a cross-head having oppositely-disposed extensions movable within 30 said cylinder opposite said slots, ball-bearing devices on said cross-head, abutments on opposite portions of the drill-rod, a drill-rod 35 mounted to reciprocate loosely through said cross-head, independent springs acting upon said ball-bearing devices and engaging said abutments on the drill-rod, pins carried by the cross-head and projecting through said 40 slots, and means connected with the said pins for reciprocating the cross-head.
